Attorney

UNITED STATES PATENT OFFICE.

FREDERICK W. KLEIN, OF SERAFINA, NEW MEXICO.

ERASER.

Application filed June 5, 1924. Serial No. 718,099.

To all whom it may concern:

Be it known that I, FREDERICK W. KLEIN, a citizen of the United States, residing at Serafina, in the county of San Miguel and 5 State of New Mexico, have invented certain new and useful Improvements in Erasers, of which the following is a specification.

This invention relates to stationery and the primary object of the invention is to 10 provide a combined pen and pencil and ink eraser attachment for pens and pencils, which can be made a part of the pen or pencil or as a separate portion thereof.

Another object of this invention is to provide a novel eraser embodying a spherical shaped head having a plurality of arcuate scraping knives formed thereon, and rubber inserts arranged between the knives.

A further object of the invention is to 20 provide novel means for connecting the spherical erasing head to the pen or pencil.

A further object of the invention is to provide a casing for receiving the erasing head and novel means for projecting the 25 erasing head from the casing.

A still further object of the invention is to provide an improved device of the above character, which will be durable and efficient in use, one that will be simple and 30 easy to manufacture, and one which can be placed upon the market at a small cost.

With these and other objects in view, the invention consists in the novel construction, arrangement, and formation of parts, as 35 will be hereinafter more specifically described, claimed and illustrated in the accompanying drawings, in which drawings:

Figure 1 is a fragmentary side elevation of the invention showing the novel erasing 40 head,

Figure 2 is a horizontal section through the erasing head,

Figure 3 is a side elevation of the device in which the erasing head is disposed with- 45 in a cap or main integral part of a pen or pencil,

Figure 4 is a longitudinal section through the form shown in Figure 3 of the draw- ings,

50 Figure 5 is a similar view showing the erasing head projected out of the casing,

Figure 6 is a side elevation of the device, and

55 Figure 7 is a modified form of the device.

Referring to the drawings in detail, wherein similar reference characters designate corresponding parts throughout the several views, the letter A generally indicates one form of the invention which comprises a spherical shaped head 10. This head 10 can be provided at equa-distantly spaced points with a plurality of arcuate shaped cutting knives 11, which can be utilized for scratching ink lines, or erasing 60 ink lines, when necessary. These knives as shown are arranged circumferentially around the head 10. This head can be formed solid or hollow, as shown in Figure 65 of the drawings. I also prefer to arrange 70 between the cutting knives 11 rubber inserts 12 which can be utilized for erasing pencil marks when desired. The rubber insert 12 can be secured in place in any de- 75 sired way and if preferred, a suitable adhesive can be used for this purpose.

While I have shown in Figure 1 of the drawings the cutting knives 11 arranged all around the head 10, one half of the head can be left smooth as indicated by the reference 80 character 13 in Figure 6 of the drawings so that the smooth portion of the head can be used to smooth down the paper after the ink marks have been erased therefrom by one of the cutting knives 11. If it is not 85 desired to leave one half of the head 10 smooth as shown in Figure 6, a portion of the upper half can be left smooth as shown in Figure 7 of the drawings and indicated by the reference character 14. 90

The improved eraser includes the cylindrical body 15 which can be considered as forming a part of a pen or pencil and which has the outer end thereof closed by a cap 16. This cap or closure plate 16 is hingedly 95 connected to the cylindrical body 15 by the use of a suitable hinge 17.

Slidably mounted within the cylindrical body 15 is a split sleeve 18 which is adapted to snugly engage the inner surface of the body so that the same will be held in any desired position in the body. The erasing head 10 is connected with the sleeve 18 in any desired way, such as by a reduced shank 19. 100

In order to force the erasing head 10 from out of the body 15, the sleeve 18 is provided with a radially extending operating pin 20 which protrudes through a longitudinal slot 21 formed in the said body. It 110

is obvious that when it is desired to move the head 10 from out of the body, the pin 20 can be grasped and forced upwardly. When it is desired to return the head inside 5 of the body the pin 20 can be again grasped and forced downwardly.

In order to permit the automatic raising of the plate or cap 16 a link 22 is provided. This link 22 is adapted to extend through 10 a slot 23 formed in the head 10 and the outer end of the link is pivoted as at 24 to the inner portion of the cap or closure plate 16 adjacent to the hinge 17 thereof. The inner end of the link 22 is pivoted as at 25 15 to the erasing head 16 and adjacent to the forward end thereof.

By this construction, it can be seen that the cutting or erasing head 10 is normally hid from view and protected from dust and 20 the like.

In Figure 7 of the drawings I have shown a modified form of the attachment indicated by the reference character B which is adapted to be used with the ordinary type 25 of pencil and is adapted to be slid on the outer end thereof. This type B of course embodies the cutting or erasing head 10 and the shank 19. The shank 19 in this instance is attached to the outer end of a relatively 30 long sleeve 26 which is split longitudinally as at 27 to permit the ready placing thereof on a pencil. Owing to the inherent resiliency of the metal from which the sleeve 26 is formed, the same efficiently grips the

pencil ends and thus prevents loss of the 35 eraser.

Changes in details may be made without departing from the spirit or the scope of this invention, but:

What I claim as new is:

1. In an eraser of the character described, a spherical head having a plurality of arcuate scratching knives formed thereon extending circumferentially thereof, and rubber strips fitted around the head between 45 the scratching knives.

2. In an eraser of the character described, a cylindrical body, a pivoted closure for one end of the body, a sliding resilient sleeve mounted within the body, a spherical head 50 formed on the sleeve provided with a diametrically extending slot, scratching knives formed on the head, and a link fitted in the slot and pivotally connecting the head with the inner surface of the cover plate. 55

3. In an ink eraser, a cylindrical body, a hinged closure cap for one end of the body, a resilient sleeve slidably mounted within the body, a head formed on one end of the sleeve provided with a plurality of radial 60 scratching knives, a link pivotally connecting the head with the cap, the body having a longitudinally extending slot therein, and a finger gripping pin secured to the sleeve extending through said slot, as and for the 65 purpose specified.

In testimony whereof I affix my signature.
FREDERICK W. KLEIN.
